UNITED STATES PATENT OFFICE.

CLARA E. JOHNSON, OF REMSEN, IOWA.

PHONOGRAPH-RECORD-FILING RACK.

1,371,766.

Specification of Letters Patent. Patented Mar. 15, 1921.

Application filed July 27, 1920. Serial No. 399,253.

To all whom it may concern:

Be it known that I, CLARA E. JOHNSON, a citizen of the United States of America, residing at Remsen, in the county of Plymouth 5 and State of Iowa, have invented certain new and useful Improvements in Phonograph-Record-Filing Racks, of which the following is a specification.

This invention relates to certain new and 10 useful improvements in phonograph record filing racks adapted to have a number of records filed therein for ready and convenient access whenever desired for use.

The primary object of the present invention is to provide an extremely simple and 15 durable rack of this kind which may be cheaply and easily manufactured as well as easily placed into practical use.

A further object of the invention is to 20 provide a record rack embodying one or more units composed of a plurality of hinged leaves which may be selectively swung to a vertical position for exposing the record upon the next succeeding lower 25 leaf horizontally positioned therebelow, the leaves being hinged at their rear edges in different vertical planes so as to allow any number or all of the leaves to be swung to a vertical position without obstruction.

A still further object of the invention is 30 to provide hinges for the rear edges of the leaves formed from sheet metal so as to also provide small pockets for reception of the edges of the records so that the latter will 35 not become easily displaced.

With the above general objects in view 40 and others that will become apparent as the nature of the invention is better understood, the same consists in the novel form, combination and arrangement of parts hereinafter more fully described, shown in the accompanying drawing and claimed.

In the drawing, wherein like reference 45 characters indicate corresponding parts throughout the several views,

Figure 1 is a front elevational view of a filing rack of the drawer type constructed in accordance with the present invention,

Fig. 2 is an enlarged fragmentary view in 50 vertical section showing a portion of the device in Fig. 1 with one of the drawers in opened or withdrawn position,

Fig. 3 is a top plan view of one of the 55 drawers removed and shown on a larger scale and broken away,

Fig. 4 is a sectional view of one of the leaves taken substantially upon line IV—IV of Fig. 3,

Fig. 5 is a view similar to Fig. 4 taken substantially upon line V—V of Fig. 3. 60

Fig. 6 is a perspective view of one of the pocket forming strips of the leaves, and

Fig. 7 is a perspective view of one of the hinge members of the leaves.

Although the present invention may be 65 embodied in many different forms and is contemplated to form part of a cabinet talking machine, the same is herein illustrated as a separate and distinct cabinet embodying a frame 5 having a plurality of sliding 70 drawers 6 arranged in superposed relation and each drawer being of similar construction and embodying a plurality of hinged leaves 7 adapted to normally assume a horizontal position for resting a phonograph 75 record 8 thereon. The cabinet may additionally embody a lower drawer 9 for miscellaneous use such as holding an index card, needles, etc.

As the construction of all of the drawers 80 6 is identical, description of one will suffice. The drawer 6 comprises a pair of side members 10 which are of increased height at their rear ends as at 11 and which are connected by a bottom wall 12 as well as front 85 and rear walls 13 and 14 respectively, the front wall 13 being of the same height as the forward ends of the side walls 10 and the rear wall 14 being of the same height as the rear ends 11 of said side walls. A 90

pair of brackets 15 is secured to the side walls 10 in opposed relation and in an upwardly and rearwardly inclined position as shown clearly in Figs. 2 and 3, and these brackets 15 are of channel form so as to 95 provide a central web spaced inwardly of the side walls 10 of the drawer. The brackets 15 are provided with a number of alined openings in the web portions thereof and substantially centrally between the sides 100 thereof from end to end, and one end of a rod 16 projects into each perforation of one bracket 15 with its opposite end projecting into the corresponding alined aperture of the other bracket. In this way a number 105 of hinged rods 16 is horizontally disposed in superposed relation transversely of the drawer upwardly and progressively nearer the rear wall 14 so that said rods 16 are all in different vertical planes. A plurality of 110

plates or leaves 17 is arranged in the drawer and each is pivotally connected for vertical swinging movement to one rod 16 by means of a pair of strips 18 which embrace the rod adjacent the brackets 15 and are secured as at 19' to the leaves 17. As the forward edges of the plates or leaves 17 are in overlapping relation, suitable data may be placed thereon for indicating the particular record upon each leaf so that such data will be at all times exposed to view for facilitating finding of the record desired at any time.

Each leaf 17 has a sheet metal strip 19 fastened along its rear edge by riveting or the like so that a wall 20 of each strip 19 is in spaced relation to its leaf 17 for providing a pocket 21 adapted to receive a marginal portion of the record 8 as shown clearly in Figs. 2 and 3 for assisting somewhat in the ready placement of the records properly upon the leaves.

In operation, the drawers 6 are properly indexed as are also the hinged leaves of each of the same. When a record is desired, the proper drawer is withdrawn and the desired ones of the leaves 17 of said drawer are swung upwardly to a vertical position for exposing the desired record upon the then uppermost horizontal leaf so that a person may readily obtain this record for use. With the records horizontally supported upon the leaves or shelf like members as contemplated and shown herein it has been found to be quite convenient and much more desirable than with the records vertically disposed as filed in the commonly used racks now on the market and in extensive use.

From the foregoing description it is believed that the construction and operation as well as the advantages of the present invention will be readily understood and appreciated by those skilled in the art.

Minor changes may be made without de-

parting from the spirit and scope of the invention as claimed.

What is claimed as new is:—

1. In a phonograph disk-record filing rack, a support, a pair of similar upwardly and rearwardly inclined alined brackets of channel form rigidly secured in spaced relation to said support and having a number of alined openings in the web portions thereof from end to end, a plurality of horizontal rods, each having one end pivotally projecting into one opening of one of said brackets with its opposite end similarly projecting into a corresponding alined opening of the other bracket, a plurality of similar record supporting leaves, and a pair of strips tightly embracing each of said rods adjacent said brackets and rigidly fastened to each of said leaves for securing one rod to each leaf. 65

2. In a phonograph disk-record filing rack, a support, a pair of similar upwardly and rearwardly inclined alined brackets of channel form rigidly secured in spaced relation to said support and having a number of alined openings in the web portions thereof from end to end, a plurality of horizontal rods, each having one end pivotally projecting into one opening of one of said brackets with its opposite end similarly projecting into a corresponding alined opening of the other bracket, a plurality of similar record supporting leaves, a pair of strips tightly embracing each of said rods adjacent said brackets and rigidly fastened to each of said leaves for securing one rod to each leaf, and a sheet metal strip fastened against the rear edge of each leaf, each having a narrow wall extending forwardly above the rear margin of its leaf, whereby a small pocket is provided for reception of the rearmost marginal portion of a record placed on said leaf. 85

In testimony whereof I affix my signature.

CLARA E. JOHNSON.
